HIRAM H. SPONENBURG, OF GURNEE, ILLINOIS, ASSIGNOR, BY MESNE ASSIGNMENTS,
TO OTTO R. BARNETT, OF CHICAGO, ILLINOIS.

RAIL-STAY.

1,214,723.

Specification of Letters Patent.

Patented Feb. 6, 1917.

Application filed February 14, 1916. Serial No. 73,170.

To all whom it may concern:

Be it known that I, HIRAM H. SPONENBURG, a citizen of the United States, residing at Gurnee, in the county of Lake and State of Illinois, have invented certain new and useful Improvements in Rail-Stays, of which the following is a specification.

My invention relates to a rail stay—that is, to a device for checking the tendency of railroad rails to creep longitudinally in the direction of the track, and more particularly to a rail stay of the type employing a spring yoke or strap member as a part of the rail clamp which extends around the base of the rail and is strained when the device is applied to the rail so that the device takes a resilient hold on the rail base, which is not detrimentally affected by the contraction of the rail or by the vibrations thereof incident to the passage of trains or by other similar influences. A device of this general type is disclosed in my Patent No. 994,795, patented June 13, 1911, in which the spring member, which is in the form of a bowed spring with a hook at each end, extends from one edge of the rail base to a tie abutting member engaging the other edge of the rail base, the intervening bowed portion of the yoke standing at some little distance away from and below the bottom of the rail. The objection to this arrangement is that the middle portion of the spring yoke is likely to be brought into contact with the ballast, with the result that the spring is flexed or flattened and the hold of the device on the rail thereby impaired. This condition may be brought about by the vibration of the rail or the rail and the tie under the impulses imparted to the rail by the wheels as they pass over it; or it may happen that the ballast will be permanently banked up under the spring yoke so that the device will not take at any time the firm hold on the rail necessary in order to check the creeping tendency thereof.

One of the principal objects of my invention is to provide a device of this general type in which the spring member is flexed at its lower point over a web or strut of one kind or another so that the contact with the ballast cannot produce any diminution in the spring action which the yoke exerts against the rail.

A further object is to provide certain arrangements whereby the spring member is engaged with the other member of the rail stay in such manner that any tendency on the part of the rail to creep increases the force of the spring action by which the engagement with the rail is effected, and whereby the coengaging elements of the device are held in proper position with each other as against any influences tending to produce a retrograde loosening movement of one with regard to the other.

My invention consists in the novel and improved constructions and arrangements shown in the drawings and which will be hereinafter described and claimed for carrying out the above stated objects, and such other objects as will appear from the following description.

Incidentally, my invention seeks to provide a rail anchor which will be extremely light and at the same time strong and economical to manufacture.

The invention is illustrated in the preferred embodiment in the accompanying drawings, wherein—

Figure 1 shows the device in elevation as applied to a rail, the latter being illustrated fragmentarily in section. Fig. 2 is a plan view of a rail fitted with the rail stay of my invention and showing also the tie against which the device abuts. Fig. 3 is a sectional view on line 3—3 of Fig. 2 and Figs. 4 and 5 are views in perspective of the members constituting this, the preferred embodiment of my invention.

It will be realized that certain changes in the form, construction and relationship of the parts might be made without departure from the principles of my invention. The invention might be utilized in connection with a rail anchor consisting of more than two parts.

Referring to the drawings, the rail is shown at 10 and one of the ties on which the rail is laid at 11.

The rail anchor consists of a jaw member 12 and a spring yoke or strap 13. The jaw member 12 is adapted to embrace one edge of the base flange of rail 10 and is preferably provided with a depending flange 14 which bears against the face of tie 11. The jaw member is formed on its under side with

a depending longitudinally extending web 15 which preferably increases in width in the direction toward the tie abutting flange 14. The outer surface of the jaw member is preferably depressed slightly, as indicated in a somewhat exaggerated manner at 16 so as to provide a seat for the yoke 13, the purpose of this being to prevent any disturbance of the operative relation between the yoke 13 and jaw member. The yoke is formed at one end with a hook 17 extending around the edge of the rail base opposite to that embraced by jaw member 12 and at the other end with a larger hook 18 which extends 15 around the said jaw member. The part 19 adjacent the hook 17 preferably lies close to the under surface of the rail base.

At about the middle of the rail the yoke takes a sharp downward bend and passes 20 around the web 15. Fig. 3 illustrates the manner in which the device is applied to the rail. The jaw member is first put in place, after which the yoke is hooked over the jaw member. The dotted lines indicate the original set of the yoke. By forcing the hook 17 up over the edge of the rail base the yoke is flexed or strained over the web 15 so that it binds the jaw member to the rail by a resilient clamping action which may be of considerable power if the yoke is made of stiff, heavy spring steel. It will be observed that the yoke is flexed over the web at substantially its lowermost point. This is not literally so in the construction shown in the drawings, but the bend in the yoke is so close to the web that the effect is the same. That is, the spring pressure exerted by the yoke cannot be diminished if the device is brought into contact with the ballast.

40 The web 15 is preferably wedge-shape, as shown—that is, its width increases in the direction toward the tie against which the device is abutted so that if the rail starts to creep carrying the yoke with it, the whole power of the device is increased, because the farther forward the yoke moves the more it will be flexed.

I claim:

1. A rail stay comprising two rail engaging members, one of which is elastic and flexed over a web formed on the other so that the device takes a resilient hold on the rail.

55 2. A rail stay comprising two rail engaging members, one of which is provided with a tie abutting portion and the other of which is elastic and flexed over a web formed on the first-named member.

3. A rail stay comprising two rail engaging members, one of which is elastic and extends around the base of the rail, engages the other member and is flexed over a web on said other member.

4. A rail stay comprising two rail engaging members, one of which is elastic and extends around the base of the rail, engages

the other member and is flexed over a web located on the under side of the other member beneath the rail base.

5. A rail stay comprising two rail engaging members, one of which is elastic and is flexed over a web formed on the under side of the other member beneath the rail base. 70

6. A rail stay comprising a jaw member adapted to embrace the edge of the base of a rail, and a spring yoke which is strained 75 when applied to the rail, having a hook at one end engaging the rail base opposite said jaw member, and a hook extending around and over the top of said jaw member.

7. A rail stay comprising a jaw member 80 adapted to embrace one edge of the base of a rail and formed with a projecting web and a spring yoke extending around the rail base and said jaw member which is flexed at a point intermediate its extremities over said 85 web.

8. A rail stay comprising a jaw member adapted to embrace one edge of the rail base 90 of a rail and formed on the bottom with a depending web, and a spring yoke having a hook at one end engaging the edge of the rail base opposite the jaw member, and a hook at the other end engaging said jaw member, the intervening portion of the yoke being flexed over said projecting web. 95

9. A rail stay comprising a jaw member adapted to embrace one edge of the base of a rail and formed on the bottom with a depending web disposed under and at a distance from the edge of the rail base, and a 100 spring yoke having a hook at one end engaging the edge of the rail base opposite the jaw member, and a hook at the other end engaging said jaw member, the intervening portion of the yoke being flexed over said 105 projecting web.

10. A rail stay comprising a jaw member adapted to embrace one edge of the base of a rail and formed on the bottom with a depending web, and a spring yoke having a hook at one end engaging the edge of the rail base opposite the jaw member, and a hook at the other end engaging said jaw member, the intervening portion of the yoke being flexed over said 110 projecting web, said 115 web extending longitudinally of the rail and increasing in width in the direction of the tie against which said web abuts.

11. A rail stay comprising a jaw member adapted to embrace one edge of the rail base, 120 formed on the bottom with a wedge-shaped longitudinally extending web, and a spring yoke engaging the rail at one end and the jaw at the other, with the intermediate portion flexed over said web. 125

12. A rail stay comprising a jaw member adapted to embrace one edge of the base of a rail and formed with a tie abutting flange, and a spring yoke which is strained when applied to the rail, having a hook at one 130

end engaging the opposite edge of the rail, and a hook extending around and over the top of said jaw member.

13. A rail stay comprising a jaw member adapted to embrace one edge of the rail base, formed on the bottom with a wedge-shaped longitudinally extending web, and a spring yoke engaging the rail at one end and the jaw at the other, with the intermediate portion flexed over said web, said jaw member formed with a depression providing a seat for said last-named hook, for the purpose described.

14. A rail stay comprising a jaw member adapted to embrace one edge of the rail base, and a spring yoke which is strained when applied to the rail, having a hook at one end engaging the opposite edge of the rail base, and a hook extending around and over the top of said jaw member; said jaw member being formed with a depression which provides a seat for said last-named hook.

15. A rail stay comprising two rail engaging members, one engaging one edge of the base of a rail and the other being resilient and embracing the first-named member and the opposite edge of the rail base, said first-named member being formed with a depression providing a seat for the resilient member.

16. A rail stay comprising a jaw member adapted to embrace one edge of the base of a rail and provided on the under side with a surface downwardly inclined toward the

tie against which the device is abutted, and a spring yoke which is flexed over said surface and engages said jaw member and the opposite edge of the rail base.

17. A rail stay comprising two rail engaging members, one of which is elastic, extends around the rail base and a part of the other member and is flexed at substantially its lowest point over a part of said other member.

18. A rail stay comprising a jaw member formed with a tie abutting flange and on its under side with a longitudinally extending web which increases in width toward said tie abutting flange, and a spring yoke having a hook extending around said jaw member, and a hook at the other end extending around the edge of the base of the rail opposite said jaw member, the intervening portion of said yoke being flexed over said web.

19. A rail stay comprising a jaw member formed with a tie abutting flange and on its under side with a longitudinally extending web, and a spring yoke having a hook extending around the edge of the rail base opposite the jaw member, and a hook at the other end extending around said jaw member, the portion of the yoke adjacent the first-named hook lying close to the under side of the rail base and the portion adjacent the other hook extending around and being flexed over said web.

HIRAM H. SPONENBURG.
